UNITED STATES PATENT OFFICE.

CHARLES H. TEXTER, OF PHILADELPHIA, PENNSYLVANIA.

MILK-BOTTLE.

1,108,023.

Specification of Letters Patent. Patented Aug. 18, 1914.

Application filed December 16, 1913. Serial No. 807,098.

To all whom it may concern:

Be it known that I, CHARLES H. TEXTER, a citizen of the United States, residing at Philadelphia, in the county of Philadelphia, 5 and State of Pennsylvania, have invented new and useful Improvements in Milk-Bottles, of which the following is a specification.

The invention relates to bottles, and more particularly to that class of bottles primarily designed for containing milk, and 10 has for an object to provide a milk bottle having a pouring spout and a means for seating the usual cap or closure on the bottle.

15 The invention contemplates, among other features, the provision of a bottle preferably formed of a piece of glass and which provides an integral head formed at the upper end of the neck, the said head having a pouring spout and providing a seat for the usual disk-like cap or closure ordinarily employed in connection with milk bottles.

20 The invention further embodies a pouring spout which, when milk is poured from the bottle, will prevent drippings of the milk from dropping on to the bottle on account of the peculiar formation of the spout.

25 In the further disclosure of the invention reference is to be had to the accompanying drawings, constituting a part of this specification, in which similar characters of reference denote corresponding parts in all the views, and in which:

30 Figure 1 is a perspective view of the bottle; Fig. 2 is a fragmentary vertical sectional view showing the construction of the upper end of the neck of the bottle; and Fig. 3 is a vertical sectional view taken through the spout, the cap having been removed from the bottle.

35 Referring more particularly to the views, I provide a bottle body 10 including an integral neck 11 terminating in an enlarged circular head 12 and which is formed to provide an outer convex face 13 and an inner convex face 14, the said outer and inner convex faces at their point of juncture being adapted to form a rounded edge 15. The inner convex face 14 terminates at its inner 40 end in an inclined inner face 16 and which is inclined toward the outer convex face 13 to form a horizontal circular seat 17 adapted to receive the usual cap 18 for closing the bottle body 10. By having the face 16 inclined as mentioned, it will be apparent that when the cap has once been wedged into

closed position on the bottle body it will be prevented from accidental removal from closed position and can only be removed by applying a suitable cap removing instrument 60 to the cap or by perforating the cap in order to partially collapse the same and then withdrawing the cap from the bottle body. A pouring spout 19 is formed with the head 12, the said pouring spout being formed above 65 the seat 17 and including a lateral portion 20 and an integral abruptly depending lip 21 formed at the outer end of the lateral portion 20. By having the lip 21 abruptly depending as mentioned, when milk is poured from the bottle, drippings of the milk will be prevented from dropping on the bottle body, as will be readily understood by referring to the views.

70 When the cap 18 is arranged in position 75 on the seat 17 the same will close the bottle body so that milk cannot be poured out of the bottle by way of the spout 19 and which is formed exteriorly of the bottle body. It will be understood that the head 12 and 80 spout 19 of the head are formed integrally with the neck 11 and that the bottle, when completed, will be a unitary element in which all the parts are integral. The lower end of the depending lip 21 preferably terminates in a knob 22 and which is provided for the purpose of aiding in preventing drippings from the milk, when the said milk is poured from the spout, from dropping on to the exterior of the bottle.

85 From the foregoing description it will be apparent that a bottle is provided of a simple and durable construction which can be cheaply manufactured and which will present a neat appearance, while at the same 90 time it will be sanitary and will permit of easily pouring milk therefrom.

95 Having thus described my invention, I claim:

100 As a new article of manufacture, a milk bottle comprising a bottle body having an integral neck, a head formed at the upper end of the neck and enlarged to provide an outer convex face and an inner convex face, with the said outer and inner convex faces 105 terminating at their juncture in a rounded edge, the said inner convex face being formed to provide an inner inclined face forming a horizontal seat in the head, with the said seat adapted to receive a cap, and 110 a pouring spout formed with the head and projecting from the outer convex face, with

the said pouring spout terminating in an abruptly depending lip having a knob at its extremity, said pouring spout being further formed to extend entirely across the said head and having its bottom at the inner end straight and at the outer end curved downwardly.

In testimony whereof I affix my signature in presence of two witnesses.

CHARLES H. TEXTER.
